FRANCIS E. JONES, OF ROYAL OAK, MICHIGAN

CLOTHES STEAMER

Application filed March 25, 1927. Serial No. 178,188.

The present invention pertains to a novel clothes steamer designed for the purpose of steaming clothing and other fabric articles by the method of passing a current of steam 5 through them.

In prior devices of this type, much difficulty has been experienced by the passage of moisture-laden or wet steam into the articles under treatment. Steam has not hitherto 10 been successfully used for cleaning silk or silk-lined garments, as it readily spots silk fabric. If an article is not destroyed in this manner, it requires at least a pressing operation to remove the wrinkles produced by the 15 moisture.

The present invention overcomes this difficulty by the use of a suitable filtering device which removes moisture from the steam before the latter penetrates the work. A system 20 is provided for draining the accumulated moisture, and in this connection precaution has been taken to prevent the drainage system from acting as a conduit of steam from one section of the apparatus to another section 25 where it may not be wanted.

The device is made in two separate chambers which divide the working surface into two sections. The steam pipes supplying the two chambers are separately regulated so 30 that steam may be admitted thereto in varying quantities or one chamber may be entirely cut off from the steam supply while the other chamber remains operative. Both steam supplies are, however, governed by a single 35 control valve which is normally closed. This valve is operated by a pedal or similar member which the operator actuates in order to admit steam to the apparatus after the work has been properly adjusted thereon.

40 The invention is fully disclosed in the following description and the accompanying drawing in which

Figure 1 is an elevation of the device;

45 Figure 2 is a plan section thereof;

Figs. 3 and 4 are sections on the lines 3—3 and 4—4 respectively of Fig. 1;

Fig. 5 is an end view;

50 Fig. 6 is a section on the line 6—6 of Fig. 2, and

Fig. 7 is a detail longitudinal section of one of the steam sprayers.

Figure 8 is a conventional view of the piping system external of the body portion, the steam circulation being indicated in heavy 55 arrows and the condensate return is indicated in dotted arrows;

Figure 9 is an enlarged cross sectional detail of the check valve.

Reference to these views will now be made 60 by use of like characters which are used to designate corresponding parts throughout.

The device is built upon a pedestal 1 provided with feet 2, and supporting at its upper end a form 3 of any shape suitable for the 65 application of clothing garments thereto. The form is preferably an elongated hollow body lying horizontally and having an enlarged depending end portion 4 mounted on the upper end of the pedestal 1 and supported 70 thereby in any suitable manner. This portion is rounded so that it may be fitted into the shoulder of a garment for effectively 75 steaming the shoulder.

The form 3 has a horizontally perforated 75 partition 5 while the top thereof is more finely perforated as indicated by the numeral 6. There is also provided a vertical partition 7 dividing the interior of the form into a forward chamber 8 and a rear chamber 9. 80

A steam sprayer and filter of the type shown in Fig. 7 is provided in each compartment beneath the partition 5. Fig. 7 shows a sprayer and filter in the forward compartment 8. This member comprises a 85 tube 10 closed at its ends and formed with perforations 11 in the lowermost part of its wall. The perforated steam supply pipe 12 enters the tube 10 at one end thereof and is substantially co-extensive therewith in length. 90 The pipe 12 supplies steam to the tube 10 as will hereinafter be pointed out, and in the annular space between these members is mounted a screen 13 of cylindrical form, the object 95 of the screen is to collect and separate such moisture as may issue from the pipe 12, so that only dry steam will be emitted through the perforations 11.

The filter and sprayer in the other compartment 9 is of similar construction and is desig- 100

nated by the numeral 14. The rear end of this member is bent into an arc 15 of approximately ninety degrees in order that the steam supply pipe 16 thereof may lie vertically.

5 Steam is supplied to the pipes 12 and 16 from an inlet pipe 17 having two elbows 18 and 19. The pipe 17 has a coupling 20 which receives a line 21 leading from the steam pipe 16 of the rear filter and sprayer 14. Directly 10 adjacent the coupling 20, the pipe 21 contains a check valve 22, and above the valve is a spring controlled valve 23 which is normally closed. Beyond the valve 23 is an adjustable valve 24 which determines the quantity of 15 steam permitted to enter the pipe 16. A branch 25 leads from the pipe 21 below the valve 24, to the steam supply pipe 12 of the filter and sprayer in the front compartment 8. This branch is provided with an adjustable valve 26 controlling the supply of steam 20 to the pipe 12. The flow of steam to both valves 24 and 26, is, however, normally shut off by the control valve 23.

In order to actuate the valve 23, there is 25 provided a finger 27 fixed to the valve casing and having pivoted thereto a trip 28 adapted to press inwardly on the valve stem 29. A pulley 30 is suspended from the form 3 and is trained by a cord 31 attached to the free end 30 of the member 28 and also to a pedal 32 on the floor as shown in Fig. 1.

The form also contains a closed circulation pipe 33 having at one end an exterior vertical portion 34 branched into the line 21 35 as indicated by the numeral 35 in Fig. 5. The other end of the pipe 33 leads directly into the pipe 17.

The condensate accumulating in the forward chamber 8 is led off through a pipe 37 40 lying mainly in the chamber 9 and having its forward end passed through the partition 7 into the front chamber. The rear end of the pipe runs into an external vertical drain pipe 38. For draining the rear compartment 9, 45 a vertical pipe 39 extends upwardly through the bottom thereof and is joined into the drain pipe 38 as shown in Fig. 5. Between the members 38 and 39 is mounted a check valve 40 which prevents steam in the chamber 8 from backing up into the pipe 37 and thence through pipes 38 and 39 to the other chamber 9. The valve acts similarly in preventing steam in the chamber 9 from flowing 50 through the same piping into the chamber 8.

To the elbow 19 is connected a steam trap 40' from which leads a final drain pipe 41. The pipe 41 is connected to the common outlet 55 of the chamber drain pipes 38 and 39 by a pipe 42 as shown in Figure 1.

60 In the operation of the device steam is admitted to the pipe 17 through an intake pipe 43 connected to the upper elbow 18. The check valve 22 prevents the steam from entering the pipe 21 except through the circulation pipe 33. Also, the trap 40 prevents

the steam from flowing directly to the exhaust end of the system. After flowing through the circulation pipe 33, the steam passes down the pipe 34 and into the pipe 21 at a point below the control valve 23.

70 The valves 24 and 26 are adjusted to emit any desired quantity of steam into the chambers 8 and 9 as already stated. If steam is wanted in only one of the chambers the valve associated with the other chamber is entirely closed. The garment to be cleaned is now adjusted on the operative part of the perforated top of the body 3, and the pedal 32 is depressed to open the valve 23 and permit entry of steam into the form. The steam passes 75 through the apertures 11 of the filter or filters to which it is supplied, and thence through the perforated partition 5 and perforations 6 in the top, whereby only dry steam penetrates the article under treatment. 80

85 The condensate formed in the circulation pipe 33 is carried by the current of steam down the pipe 34 and into the pipe 21, whence it flows toward the check valve 22. Although this valve prevents passage of steam therethrough from the coupling 20 to the pipe 21, it is of such construction as to permit water to leak therethrough from the pipe 21 to the drain elbow 19.

90 Although a specific embodiment of the invention has been illustrated and described, it will be understood that various alterations in the details of construction may be made without departing from the spirit of the invention as indicated by the appended claims. 95

What I claim is:

1. A steam cleaner comprising a hollow body having apertures in its upper wall, a perforate steam supply pipe adapted to emit steam into said body, a filter sleeved over said pipe throughout the perforate length thereof and adapted to retain moisture, and a tubular casing pipe closed at its ends and enclosing said pipe and filter and provided with apertures in its lower side to direct steam downwardly, whereby moisture is prevented from reaching said apertures. 105

2. A steam cleaner comprising a hollow body having apertures through its wall, a perforate steam supply pipe adapted to emit steam into said body, a filter sleeve over said pipe and adapted to retain moisture, a tubular casing enclosing said pipe and filter and provided with openings for the escape of steam, and means for draining the moisture 110 from said body. 115

3. A steam cleaner comprising a hollow form having a downwardly projecting rounded end portion with an arm extending laterally therefrom and shaped to fit into the shoulder of a garment, and provided with apertures in the upper wall thereof, means for admitting steam into said form, moisture filtering means between said steam admission means and said apertures, and a partition 125 120

in said form separating said shoulder portion from the remaining portion thereof, whereby steam may be admitted to either portion of the form independently of the other and moisture is prevented from reaching said apertures.

4. A steam cleaner comprising a hollow body formed with a downwardly projecting rounded end portion with an arm extending laterally therefrom and having apertures through its upper wall, and provided with a transverse partition dividing the same into separate chambers, a steam supply pipe adapted to emit steam into each of said chambers, a filter applied over each of said pipes and adapted to retain moisture, whereby to prevent moisture from reaching said apertures, a steam circulation pipe extending from end to end of said body, drain pipes having a common outlet for draining moisture from each of said chambers, and means for preventing steam in one of said chambers from entering the other chamber through said drain pipes.

5. A steam cleaner comprising a hollow body having apertures through its upper wall, and formed with a garment shoulder engaging end portion, a transverse wall in said body dividing said body into separate chambers, perforated steam supply pipes provided in said body for said chambers, a moisture filtering screen surrounding the perforations of said pipe, and an enclosure around said screen having perforations for the escape of steam into said chambers.

6. A steam cleaner comprising a body divided into compartments, steam admission means to said compartments, drain pipes leading from said compartments and having a common outlet, one of said drain pipes extending through one of said compartments and opening into the other, and means for preventing passage of steam through said pipes from one compartment to another.

7. A device of the character described comprising a hollow body having an enlarged depending end portion rounded at its upper side and forming a shoulder portion and an extended tapering arm portion projecting laterally from said shoulder portion, the upper wall of said arm portion and rounded shoulder portion being perforated, means attached to said depending end portion for supporting said body, a partition in said body intermediate the ends of said arm portion extending transversely thereof and dividing the body into separate chambers, separate means for supplying steam to each of said chambers, and a drain pipe extending within and longitudinally of the shoulder portion and open through said partition into said chamber in the arm portion to drain water of condensation therefrom and conduct the same outwardly through the shoulder portion.

8. A device as characterized in claim 7 and further characterized by having a drain pipe opening into said chamber of the shoulder portion and joining said other drain pipe in a common outlet, and means for preventing steam in one of said chambers from entering the other chamber through said connected drain pipes.

In testimony whereof I affix my signature.

FRANCIS E. JONES.
